WELDING BELL CUSHION

Harry E. Gross, Wyomissing, Pa., assignor to
Reading Iron Company, Reading, Pa., a corpora-
tion of Pennsylvania

Application April 21, 1931, Serial No. 531,719

6 Claims. (Cl. 205—25)

In the practice of making butt-weld pipe, a bell is used for forming or bending the hot strip and welding the edges. In the operation of making pipe the strip is drawn thru this bell at welding temperature. A rigid holder is now used to support the bell during the operation of drawing the skelp or strip thru the bell for forming and welding.

5 My invention consists in a cushion device as a means of supporting the bell in its operating position, instead of the rigid block now used for this purpose.

10 My invention is especially applicable in the production of butt or bell weld wrought iron pipe, altho I do not limit my invention to this use, as it is also applicable in the production of pipe of steel or other metals, produced by the butt or bell weld method of manufacture.

15 In the present operations, the welding bell is thrown over tongs which draws the strip from the furnace thru the bell, and as the end of the strip strikes the bell as the strip passes out of the furnace at a high speed (some 320 feet per minute in the production of wrought iron pipe, and over 400 feet per minute in the production of steel pipe), the bell is pulled against a rigid bell holder, which causes a shock or a blow, which blow in many cases tears off the end of the strip, causing furnace scrap and delays in operations.

20 With my invention the bell, instead of striking a rigid block, is pulled against the face of a cushion plate which minimizes the jar or shock, and reduces considerably the losses of material and the number of delays in operation.

25 My invention also provides means for alignment of the bell to the strip in the process of forming and welding.

30 My invention further provides means of knowing the amount of pull being applied to the strip as it passes thru the bell in the process.

One object of my invention is to minimize the shock caused by pulling the bell against the bell block at the initiation of the drawing period.

35 A further object of my invention is to provide means which allows the bell to align itself during the process of drawing the strip thru the bell.

40 A further object of my invention is to provide means for ascertaining whether the diameter of the bell is properly adjusted to the width and thickness of the strip. This is provided by determining the position of the cushion plate relative to the rigid bell block.

45 Other objects of my invention will be apparent. My invention can best be described by referring

to the accompanying drawing which form a part of this specification, and of which

Figure I is a plan view of one embodiment of my invention in which the cushioning effect is obtained thru the use of springs and an elastic or semi-elastic medium operating in a cylinder.

Figure II is an end view of my invention and refers equally well to Figure I, III and IV.

Figure III is a plan view of an alternate embodiment of my invention in which the cushioning effect is secured thru the operation of an elastic or semi-elastic medium in a cylinder alone.

Figure IV is another alternate embodiment of my invention in which the cushioning effect is secured by means of springs alone.

50 In all the figures, like numbers refer to the same or similar parts, and referring particularly to Figure I, the operation of my invention is as follows.

55 Skelp or strip 1 from which the pipe is produced is shown as being pulled from the furnace (not shown) by the tong 2 thru the bell 3. The means for pulling the tongs is not shown as any well-known method may be used. In the figure the bell 3 is shown in the position immediately prior to its abutment against the removable wearing piece 5, adapted to be attached to the striking plate 6. This striking plate 6 is supported from the rigid bell holder 7 by means of the elastic devices 8, the holder 7 thus forming a support for the striking plate through the elastic devices. The holder 7 is preferably mounted in a housing 17 and provided with flanges 18 received within guide grooves 19 in that housing, the guides thus formed being shown as extending vertically and permitting removal of the entire unit formed of the striking plate, support, and devices, for purposes of repair or replacement.

60 This is of particular advantage where it is desired to use another size bell for forming a different size pipe. The grooves 19 are slightly larger than the flanges in the line of movement of the pipe and thus it will be seen that as the bell strikes the plate 6, this plate may adjust

65 itself to a position such that the bell edge will be parallel to the plate and bear firmly against it, the guide grooves preventing any substantial movement of the support lengthwise of the pipe.

70 In other words, the plate 6 will be normal to the line of movement of the pipe. It will also be seen that the holder has an opening therein disposed in line with another opening in the striking plate

75 so that the tongs 2 and the welded pipe may pass therethrough. In this figure four devices are

shown, but I do not limit myself to four as any convenient number may be used.

As illustrated in Figure I, each of the elastic supports 8 consists of the cylinder 9, co-acting 5 with a tight fitting plunger 10. A compression spring 11 is interposed between the face of the plunger 10 and the head 12 of the cylinder 9.

The pipe 13 allows fluid under any desired 10 pressure to enter or leave the cylinder 9. This pipe is controlled by any suitable valve 4. Either gaseous or liquid medium may be used as the fluid in the cylinder, and in this connection I prefer the use of air, but oil, water, or any other suitable fluid may be used.

15 When air is used as a cushioning medium the pipe connection 13 and the valve 4 may be omitted, and in this case the air contained within the cylinder acts as a cushioning means in cooperation with the spring 11, and further, the 20 air under pressure in the cylinder in cooperation with the spring 11 serves to return the striking plate to its initial position, and it is limited in its outward movement by abutting against the shoulder 14.

25 Port 15, uncovered by the plunger 10, at its outermost position may be provided to renew the air supply after each operation.

The operation of my invention is as follows. The bell 3 is placed over the tongs 2 which are 30 then attached to the strip or skelp 1. The tongs are pulled by suitable mechanism, thereby drawing the strip 1 against the bell 3. On further pulling the bell 3 with the skelp 1 strikes the wearing piece 5 of the striking plate 6. The inertia of the bell, tongs, and skelp, together with the force applied to the tongs, pulls the wearing piece 5 and the striking plate 6, as well as the plunger 10, in the direction of the force and the motion of the tongs and this movement is 35 resisted by the action of the spring 11 and the elastic properties of the air entrapped in the cylinder. The impact will pull the striking plate beyond the point at which it will be maintained in equilibrium by the normal pull of the skelp, and after the force of the impact has been absorbed the striking plate will move in a direction opposite to that of the pull of the tongs and will reach a position of more or less equilibrium at some location between its limits of travel. I 40 prefer that the shock absorber be of such proportion that, when the bell is of proper size for the strip being formed and welded, the position taken by the striking plate will be about midway between its extreme positions. With the shock absorber so proportioned, if the bell is too small 45 for the strip, the striking plate will be carried forward in the direction of drawing to a position past the midway point and if the bell is too large, its equilibrium point will be reached prior to the mid position. By observing the position 50 of the striking plate, the operator is thus able immediately to determine if the bell is in proper relation to the skelp. Further, by providing elasticity at several points around the circumference 55 of the bell, the striking plate is able to adjust its position with reference to the bell and to irregularities in the strip. After the strip has passed through the bell, the force which is exerted on the striking plate by the motion of the tongs will be released and the striking plate will 60 return to its initial position due to the force of the compressed spring and the expansion of the entrapped air. I find that this return motion is not of such a violent nature that cushioning is 65 required to break its force, but such return cushioning device may be incorporated in my device under certain conditions of operation. If my cushion is properly proportioned, the force of the return motion is sufficient to eject the bell 3 from the wearing piece 5 of the striking plate 6, and it is desirable to design my cushioning device in such a manner that this ejection of the bell occurs.

If liquid is used as the cushioning mechanism, the port 15 is omitted and valve 4 serves as a constriction thru which the liquid is ejected, thus providing the flexibility needed in a device of this kind, and also as a means of returning the liquid to the system.

Figure III is substantially the same as Figure I. However, in this case the spring 11 has been omitted, and the flexibility of the connection is obtained entirely by the elasticity of the medium within the cylinder. In this figure the bell 3 is shown in position against the wearing piece 5 and the striking plate 6, and a certain amount of the strip is shown as having been formed and welded into pipe.

Figure IV is similar to Figure I, except that the cylinder 9 with the plunger 10 has been omitted, and the flexibility of the connection is obtained entirely by means of the spring 11. This is the preferred embodiment of my invention. In this figure also the bell 3 is shown in position in contact with the wearing piece 5 and the striking plate 6. Also the nuts 16 serve as an equivalent of the shoulder 14 shown in Figure I.

In this form, the springs 11 surround bolts 20 which are loosely received in the holder or support 7, and therefore can adjust themselves to aid in maintaining the striking plate 6 normal to the line of movement of the pipe. However, even in this form, I have shown the holder provided with the loose engagement with the housing as in the other forms.

Other modifications are applicable to my invention. For instance—

A tension spring properly mounted may be used in place of a compression spring, or other elastic and flexible devices and materials may be inserted between the striking plate and the rigid bell holder without departing from the spirit and scope of my invention.

What I claim is:—

1. In a device for forming pipe by drawing skelp through a bell, a striking plate for the bell having an opening therein for the passage of pipe therethrough, a support spaced from the plate along the line of movement of the pipe and having an opening substantially in line with said opening in the plate, and at least three resiliently yieldable devices spaced around said openings and extending between said support and plate and supporting the plate directly and solely from the support.

2. In a device for forming pipe by drawing skelp through a bell, a striking plate for the bell having an opening therein for the passage of pipe therethrough, a support spaced from the plate along the line of movement of the pipe and having an opening substantially in line with said opening in the plate, and at least three resiliently yieldable devices spaced around said openings and extending between said support and plate and supporting the plate directly and solely from the support, each of said devices being yieldable independently of the others.

3. In a device for forming pipe by drawing skelp through a bell, a striking plate for the bell having an opening therein for the passage of pipe therethrough, a support spaced from the plate

along the line of movement of the pipe and having an opening substantially in line with said opening in the plate, at least three resiliently yieldable devices spaced around said openings and 5 extending between said support and plate and supporting the plate directly and solely from the support, each of said devices being yieldable independently of the others, and means loosely engaging said support to permit limited tipping thereof with respect to said line of movement of the pipe.

10 4. In a device for forming pipe by drawing skelp through a bell, a striking plate for the bell having an opening therein for the passage of pipe therethrough, a support spaced from the plate along the line of movement of the pipe and having an opening substantially in line with said opening in the plate, and four resiliently yieldable devices extending between said support and plate 15 and supporting the plate directly and solely from the support, said devices being disposed in pairs on opposite sides of said opening.

20 5. In a device for forming pipe by drawing skelp through a bell, a striking plate for the bell

having an opening therein for the passage of pipe therethrough, a support for said plate, means holding said support against movement lengthwise of the pipe, said support being removable from said means by movement transversely of the pipe, and a plurality of devices yieldable lengthwise of the pipe and connecting the striking plate to the support and supporting the plate directly and solely from the support.

6. In a device for forming pipe by drawing skelp through a bell, a striking plate for the bell having an opening therein for the passage of pipe therethrough, a support spaced from the plate along the line of movement of the pipe and having an opening substantially in line with said opening in the plate, resiliently yieldable devices spaced around said openings and extending between said support and plate and supporting the plate directly from the support, and vertically extending guides slidably engaging said support 90 and holding it against movement lengthwise of the pipe while permitting its movement vertically.
